FIG. 2. INVENTOR

Althea T. Berry
by Right from Lucy May

ATTORNEYS

UNITED STATES PATENT OFFICE.

ALTHEA THOMPSON BERRY, OF WOLFEBORO, NEW HAMPSHIRE.

INNERSOLE.

1,412,603.

Specification of Letters Patent. Patented Apr. 11, 1922.

Application filed April 23, 1921. Serial No. 463,798.

To all whom it may concern:

Be it known that I, ALTHEA T. BERRY, a citizen of the United States, residing at Wolfeboro, in the county of Carroll and 5 State of New Hampshire, have invented new and useful Improvements in Innersoles, of which the following is a specification.

This invention relates chiefly to an inner sole, adapted to be inserted loosely in a shoe 10 as a slip inner sole.

The invention is embodied in an improved laminated inner sole structure having the desirable qualities and advantages hereinafter set forth.

15 Of the accompanying drawings forming a part of this specification,—

Figure 1 is a top plan view of my improved inner sole.

Figure 2 is a bottom plan view of the 20 same.

Figure 3 is a section on line 3—3 of Figure 1.

The same reference characters indicate the same parts in all of the figures.

25 In the drawings, 12 represents a sole-shaped top layer, having a smooth non-irritant foot-bearing surface, and preferably composed of leather, a thin split leather being preferred, because this variety of leather 30 is somewhat porous and permits the seepage through it of perspiration from the foot. 13 represents a sole-shaped bottom layer of soft, resilient, vulcanized rubber, and provided with a multiplicity of orifices 14,

35 formed by cutting out portions of the layer. These orifices, by interrupting the continuity of the layer, increase its resilience, so that the layer expands more freely edgewise when 40 its thickness is decreased by compression, than would be the case if the layer were imperforate.

45 15 represents a sole-shaped intermediate layer composed of absorbent and resiliently compressible fibrous material, such as wool, the layer 15 being preferably cut from a sheet of knitted woolen fabric.

50 The intermediate layer is adapted to absorb perspiration seeping through the top layer, without being matted, or permanently compressed or condensed, the nature of the fibers of which it is composed being such that they will not pack solidly together when wet. The intermediate layer, therefore, yields to compressive pressure tending to reduce its thickness, and is adapted to return

to its normal thickness on the removal of such pressure.

The orifices in the rubber layer 13 allow some of the moisture absorbed by the intermediate layer to pass through the rubber 60 layer and be absorbed by the outer sole, or by the permanent inner sole of the shoe, so that the bottom of the foot is kept relatively dry.

Moisture seeping from below through the 65 shoe bottom will not seep through the imperforate portions of the rubber layer. Such limited quantities of this moisture as may pass through the orifices 14, will be entirely absorbed and retained by the intermediate 70 layer 15, without seeping upward through the top layer, so that the foot-bearing surface is protected against moisture from the outside.

The porous and springy intermediate layer 75 cooperates with the apertured rubber layer in providing a desirable cushion, the effectiveness, life and durability of each layer being increased by its association with the other. The improved insole has a flexibility 80 and a resilient compressibility not possible in a sole of equal thickness made in a single layer, or one which includes air cells adapted to stand up under pressure, the sole being adapted to conform to movements of the 85 foot in any direction, and to locally assume its normal form when pressure is released at one portion and applied at another portion of the foot-bearing surface.

90 Wool and rubber are poor conductors of heat and cold, so that my improved insole tends to preserve the normal temperature of the foot by protecting it from either warm or cold surfaces.

95 The layers may be united by any suitable means, to permit the handling of the sole as a single part. As here shown, the marginal portions of the layers are united by a fastening thread 20, passed through some of the orifices 14 in the bottom layer, through the 100 intermediate and top layers, and across the margins of the assembled layers. Said thread may be of any suitable fibrous material, or of wire.

105 The described laminated flexible insole may be permanently incorporated in a shoe, and attached to other component parts thereof, in any suitable way. For example, an inner sole of the laminated construction described, may be secured to the upper and 110

outer sole of a McKay-sewed shoe, or to the upper and welt of a welt shoe, the top layer 12 being sufficiently substantial, or if desired, suitably reinforced to support McKay 5 stitches, or inseam stitches.

I claim:

1. A laminated flexible insole, comprising a top layer of porous material, having a smooth, non-irritant foot-bearing surface, 10 and a plurality of supporting layers, each resiliently compressible between the top layer and a supporting sole, and each adapted to assume its normal thickness on removal of compressing pressure, said supporting layers including a bottom layer of 15 soft resilient rubber, having a multiplicity of perforations whereby its resilience is increased, and an intermediate layer of absorbent material, interposed between the 20 top and bottom layers, the porosity of the top layer and the perforations of the bottom layer permitting the absorption, by the intermediate layer, of moisture from above and below the latter.
- 25 2. A laminated flexible insole, comprising a top layer of porous material, having a smooth non-irritant foot-bearing surface, a resiliently compressible bottom layer adapted to bear on a supporting sole, and composed of soft resilient vulcanized rubber, 30 having a multiplicity of orifices whereby its resilience is increased, and an intermediate

layer interposed between the bottom and top layers, and composed of absorbent knitted woolen fabric, adapted to yield to compressive pressure, and to return to its normal thickness after the removal of such pressure, 35 said bottom and intermediate layers being simultaneously compressible between the top layer and a supporting sole, the porosity of 40 the top layer, and the perforations of the bottom layer permitting the absorption, by the intermediate layer, of moisture from above and below the latter.

3. A laminated flexible insole, comprising 45 a top layer of porous imperforate leather, presenting an uninterrupted foot-bearing surface, and a plurality of supporting layers, each resiliently compressible between the top layer and a supporting sole, and each adapted 50 to assume its normal thickness on removal of compressing pressure, said supporting layers including a bottom layer of soft resilient rubber, having a multiplicity of perforations whereby its resilience is increased, and an 55 intermediate layer of absorbent material, interposed between the top and bottom layers, the porosity of the top layer and the perforations of the bottom layer permitting the absorption, by the intermediate layer, of 60 moisture from above and below the latter.

In testimony whereof I have affixed my signature.

ALTHEA THOMPSON BERRY.
